UNITED STATES PATENT OFFICE.

HENRY MURDOCK RICH, OF ATHOL, AND EDWARD LOVELL TAFT, OF GARDNER, MASSACHUSETTS.

MACHINE FOR KNITTING RATTAN.

SPECIFICATION forming part of Letters Patent No. 544,443, dated August 13, 1895.

Application filed October 24, 1888. Serial No. 289,072. (No model.)

To all whom it may concern:

Be it known that we, HENRY MURDOCK RICH, residing at Athol, and EDWARD LOVELL TAFT, residing at Gardner, in the county of Worcester and State of Massachusetts, citizens of the United States, have invented certain new and useful Improvements in Machines for Knitting Rattan, of which the following is a specification, containing a full, clear, and exact description of the same, accompanied by drawings representing a knitting-machine for knitting rattan, embodying our invention, and in which—

Figure 1 represents a front view of the rattan-knitting machine, with a portion of the supporting framework removed in order to more clearly disclose the operating parts of the machine. Fig. 2 is a side view of the machine, showing the left-hand side. Fig. 3 shows a side view of the machine with a portion of the framework removed in order to show the operating parts contained within the shell or case forming the frame. Fig. 4 is a rear view of the machine. Fig. 4^a represents a rear view with a portion of the loop-withdrawing mechanism removed and with the ring carrying the loop-holders with its supporting-stand also removed, and showing the mechanism for imparting an intermittent rotary motion to the loop-withdrawing mechanism. Fig. 5 represents in enlarged view a portion of the mechanism by which an intermittent feeding motion is given to the loop-holders. Fig. 6 represents a side view of one of the loop-holders and connected mechanism by which the loop is formed. Fig. 7 shows one of the loop-holders with its sliding block 50 in its highest position on the post 46. Fig. 8 represents the sliding block 50 detached and in perspective view. Fig. 9 is a side view of one of the loop-holders and connected mechanism for forming the loop, (shown partially in sectional view,) as indicated by the broken line X X in Fig. 16. Fig. 10 is a side view of one of the loop-holders, showing the position of the operating parts as the needle is transferring a loop to the loop-holder. Fig. 11 represents a rear view of a portion of the loop-former 65, showing the prongs or front jaws 80 81 and the vertical walls 71 71. Fig. 12 represents a rear view of one of the loop-

holders and connected mechanism for forming the loop. Fig. 13 shows the upper end of the needle in rear view. Fig. 13^a shows the upper end of the needle in side view. Fig. 14 55 is a cross-sectional view of the needle on line X' X', Fig. 13. Fig. 15 represents a portion of one of the back jaws for holding the strand of rattan. Fig. 16 is a top view of the strand-holding jaws in their position as a loop is being formed by the action of the reciprocating needle. Fig. 17 is a top view of the strand-holding jaws in their position after a loop has been formed, the needle withdrawn, and the front jaws moved a short distance with the 60 loop-holder. Fig. 18 is a top view of the strand-holding jaws in their position at the end of the forward rocking motion of the jaws, showing the strand as having been transferred to the back jaws. Fig. 19 shows 70 a top view of the strand-holding jaws in their position as the front jaws are being moved back into alignment with the needle. Fig. 20 represents in detached view a portion of the mechanism for withdrawing the loops, and 75 showing the relative positions of the loop-holder and withdrawing-link before the link has been pushed back by the sliding plunger 152. Fig. 21 represents the same mechanism as Fig. 20, but with the sliding plunger 152 shown 80 in central sectional view and with the parts of the mechanism shown in their relative position after the plunger has pushed the hooked link 124 back. Fig. 22 represents a sectional plan view of the loop-former 65 and arm 84 pivoted on coincident axes on line X² X², Fig. 6. Fig. 23 shows the end of the link 77 in perspective view and illustrates its connection with the end of the lever 73. Fig. 24 shows a rear view of the reciprocating needle 26, with a side 90 view of the strand-retaining walls 110 and a portion of the strand-tube partly in central sectional view. Fig. 25 represents in detached view the actuating-links 77 and 87, with the link 87 detached from the oscillating-lever 18. 95 Fig. 26 represents in diagrammatic view the three loops and one of the hooked withdrawing-links, showing their relative position as a loop is being formed by the reciprocating needle. Fig. 27 shows three loops and a hooked link in their relative position as the hooked link has been forced forward to engage a new 100

- loop by means of the cam-plate 130. Fig. 28 shows the same in their relative position as the link has been forced back by the cam-plate 126, so the hook 125 shall engage the loop 175. Fig. 29 shows the same in their relative position as the hooked link is pushed back by the sliding plunger, the loop 174, in Figs. 26 and 27, as held upon the tongue 51 and at right angles to the loops 175 and 176, which forms a portion of the fabric already knit. In Fig. 28 loop 174 is shown in its position at an oblique angle with the knit fabric, as represented by the loops 175 and 176, the loop 174 being held upon the tongue 51 after the post 46 has been raised by the cam-plate 117. Fig. 30 represents a section of the knit fabric as being applied to the frame of a chair-back. Fig. 31 represents a side view of the knitting-machine, showing the right-hand side. Fig. 32 represents a rear view of the loop-former 65, as shown in Fig. 11, but with the jaw 81 corrugated or provided with sharp teeth, by which the strand of rattan is slightly indented as it is bent around the jaw as a fulcrum; and Fig. 33 represents one of the loops, showing the indentations as formed by the jaw 81 and the toothed wheel 107 in the process of bending the strand. Similar parts in the several views are denoted by similar figures.
- The object of our present invention is to produce a knitting-machine by means of which a continuous tubular web of rattan may be knit from a continuous strand of rattan; and it consists in a row of loop-holders arranged in a circle and having an intermittent feeding motion by which each successive loop of the knit fabric is moved along in the proper position to receive a new loop; in the connected operating mechanism by which the intermittent feeding motion is imparted to the row of loop-holders, and in certain modifications in the mechanism for forming the loops, which are improvements upon the loop-forming devices which were shown and described in Letters Patent of the United States No. 299,295, granted to us on the 27th day of May, 1884; in providing mechanism for withdrawing the loops from the loop-holders; in the device for facilitating the bending of the strand of rattan and preventing the splitting of the same while being formed into a loop, and in the construction and arrangement of the operating parts, as hereinafter described, and specifically set forth in the annexed claims.
- In the accompanying drawings, 1 denotes a supporting stand or table supporting the operative parts of the machine.
- 2 is a shell or case inclosing the main actuating parts, and within which, journaled in bearings attached to the shell, is the main driving-shaft 3, having the hand-wheel 4, and driving-belt pulley 5 running loosely upon the shaft 3, and connected therewith when desired by means of the clutch 6.

7 is a cam having a suitably-shaped cam-slot upon its face, by which the lever 8 is given an oscillating motion about the stud 9, Fig. 4, thereby imparting a reciprocating motion to the feed-rack 10.

11 denotes a cam upon the main shaft, by which a vibratory motion is imparted to the radial arm 12 attached to the rock-shaft 13, which also carries an arm 14 connected with a vertically-sliding plate 15. The rock-shaft 13 is journaled in bearings attached to the top of the supporting-table 1, and the vertically-sliding plate 15 slides in ways attached to the table 1.

16, Fig. 1, denotes a bearing to the main shaft 3, supported by a bracket attached to the shell 2, but shown as broken away in the drawings, to disclose the operating parts at the rear of the machine.

17 is a cam attached to the main shaft 3 and having a cam-slot upon its side, by which an oscillating motion is given to the lever 18, Figs. 1 and 3, upon its stud 19, held by the shell 2.

Upon the inner end of the main shaft 3 is placed the crank-disk 20, having a crank-pin 21 working in the slot 22 of the plate 23, Fig. 3, sliding in vertical ways in a stand 24 attached to the table 1. The slotted piece 23 is provided with an arm 25, Fig. 3, to which the needle-bar 26 is attached, and the slot 22 is so formed that the rotation of the crank-pin 21 causes an intermittent reciprocating movement of the needle-bar 26, as hereinafter described.

To the top of the table 1 is attached the arched stand 27, Fig. 4, extending upward at the rear of the machine and with the stand 28 supporting the four equidistant studs 29, upon which are placed rolls entering a slot in the ring 30, one of the rolls 29^a being shown in Fig. 6. Lugs 31 project from the stands 27 and 28, holding studs 32, which carry rolls 33, resting against the back side of the ring 30, and upon the front side of the arched stand 27 are lugs holding studs carrying rolls 34, resting against the flange 35 of the ring 30, three of the rolls being shown in Fig. 1. The ring 30 is thus supported upon the rolls 29^a, placed in the concentric T-shaped slot 29^b of the ring 30 and moved with an intermittent rotary motion by means of the rack 10 alternately engaging the teeth 36 on the ring 30, the two cams 7 and 11 being so timed that as the rack is moved toward the left the vertically-sliding plate 15 is moved up, so as to bring the rack 10, which rests thereon, into engagement with the teeth upon the ring 30, and as the rack 10 is moved toward the right, Fig. 5, the plate 15 is lowered, allowing the rack to be moved back out of mesh with the teeth in the ring. The sliding movement of the plate 15 is also made to oscillate a lever 37 about its stud 38, which imparts a sliding motion to the locking-bar 39, provided with teeth 40, which engage the teeth of the ring

30 as the plate 15 is moved downward, withdrawing the teeth of the rack 10 from the teeth of the ring 30.

The rack 10 has a reciprocating motion 5 along ways in the upper edge of the plate 15, and also in the end of the arm 15^a, attached to the plate 15, while the plate 15 has a vertical motion timed to correspond with the reciprocating motion of the rack 10, so that the 10 ring is moved with an intermittent motion in the direction of the arrow 15^b, Figs. 1 and 5, the ring 30 being held during its period of rest by means of the sliding bar 39. Attached concentrically to the ring 30 is a row of loop-holders 41, one of which is shown more clearly in an enlarged view in Fig. 6. The loop-holder consists of a foot 42, held in a rectangular recess 43 in the face of the ring 30 by means of a screw 44 entering a hole 45 in the ring. 15 To the foot 42 is hinged a post 46, consisting of a rectangular bar of steel, to which the rectangular collar 47 is attached by the screw 48, which also serves to attach the curved blade-spring 49 to the collar 47. Capable of sliding 20 upon the post 46 is a sliding block 50, Fig. 8, which is provided with a circular tongue 51, hinged to the lower end of the sliding block 50, a pin 52 projecting from the side of the block 50, a pawl 53 pivoted upon the side of 25 the block opposite the pin 52 and acted upon by the pawl-spring 53^a, and a stud 54 terminating in the pin-shaped projection 55. The circular-shaped tongue 51 has about half of its upper surface raised at 56, the raised portion entering a depression 57 when the tongue is raised in the position shown in Fig. 7, and it is also provided with a semicircular groove 58 around its front edge to receive the strand of rattan forming the loop. During the 30 period of rest of the ring 30 one of the attached loop-holders is held directly over the vertically-reciprocating needle 26, and the ring 30 is moved by the action of the feeding mechanism above described, as actuated by the 35 cams 7 and 11 a distance equal to the space from the center of one of the loop-holders to the center of the next loop-holder, so that the feeding motion of the ring 30 serves to bring the several loop-holders consecutively into 40 alignment with the needle 26, allowing the successive loops, as formed by the loop-forming mechanism, to be placed upon the grooved tongues 51 of the loop-holders 41.

Pivoted upon a stud 59, held in a bracket 60, 45 attached to the case 2, is a lever 61, whose lower end is connected by a link 62 with the reciprocating rack 10, so the motion of the rack will cause an oscillating motion of the lever 61 simultaneously with the feeding motion of the ring 30. The upper end of the oscillating lever 61 is provided with the arm 63 50 64, (shown in enlarged view in Fig. 12,) in which is pivoted the loop-former 65, having the two prongs 66 and 67, by which it is pivoted to the arms 63 64, the prong 66 turning upon the pin 68 and the prong 67 being attached to the pin 69, which turns in the arm 55

64. To the upper side of the loop-former is attached a plate 70, having the upwardly-projecting walls 71, forming abutments between which the loop is forced by the upward motion of the needle 26, as shown in Fig. 12, in which 72 denotes a loop formed between the abutments 71 by the needle 26. To the pin 69 is attached a lever 73, carrying a stud 74, 75 journaled in a block 74^a sliding in the slot 76 in the link 77, Fig. 6. The link 77 is hooked upon a stud 78, carried in the upper end of the lever 18, and an arm 75 extends upward from the lever 77 through an opening in the case 2, its upper end forming a handle, whereby the operator can connect and disconnect the lever 77 and the stud 78. The loop-former 65 is also provided with a mortise 79 to receive the loop held upon the grooved tongue 51 and a 80 pair of prongs 80 81 with their under surfaces curved, termed the "front" jaws, the jaw 80 having a projecting-pin 82, by which the pivoted back jaws are actuated, as hereinafter described, and the jaw 81 serving as a fulcrum 85 around which the strand of rattan is bent as the loop is made by the upward motion of the needle 26. Pivoted upon a bracket 83, Fig. 9, which is attached to the shell or case 2, is an arm 84, capable of a swinging motion 90 about the pivotal pins 85 85^a, the axis of its motion being coincident with the axis of the loop-former 65, and from the arm 84 a lever 86 extends downward with a link 87 pivoted to its lower end. The link 87 is provided 95 with a hook by which it is hooked upon the stud 78 in the end of the lever 18, and it also has an arm 88 extending upward through an opening in the case 2, forming a handle by which the link 87 can be disconnected from 100 the lever 18 in the same manner as the link 77. When both links 77 and 87 are connected with the lever 18, the oscillations of the lever 105 actuated by the cam 17 will cause a simultaneous swinging motion of the loop-former 65 110 and the arm 84 about coincident axes, the front and back jaws being made to swing back and forth at stated intervals with a short angular motion about a common axis, which is coincident with the pivotal pins 68 69 and 115 85 85^a. In addition to the swinging motion on the pins 68 69, the loop-former 65 has a motion about the stud 59 as it is carried by the lever 61. Thus when the rack 10 is moved toward the left, Fig. 5, with its teeth in mesh 120 with the teeth 36 of the ring 30, moving the ring 30, as described, the lever 61 is also moved about the stud 59, carrying the vertical walls 71 71 along with the loop-holder, which they inclose, the space between the 125 arms 63 and 64 being sufficient to allow this angular movement of the lever 61 without bringing the prongs 66 67 of the loop-former in contact with the bracket 83 or arm 84 carrying the back jaws. 130

In order to maintain the operative connection between the lever 73 and the actuating-lever 18 through the link 77, the end of the link is provided with a slot 76, through which

the block 74^a has a transverse and longitudinal sliding motion, the link 77 being held by an arm 89 attached to the case 2, and through which the link 77 slides as it is operated by 5 the actuating-lever 18.

The back jaws 90 91 are pivoted upon the arm 84 by means of the screws 92 93, and each of the jaws has an arm 94 95, the arm 94 carrying a pin 96, which is journaled in a block 97 held in and capable of sliding within the opening 98 in the arm 95. The back jaws are thus connected so the movement of one about its pivotal screw will cause the simultaneous and similar movement of the other jaw in the 15 opposite direction. The jaw 90 has a recess forming a shoulder 99, and the jaw 91 has a similar recess in which is pivoted a pawl 100, which is held against a shoulder 101 on the jaw 91 by means of the spring 102, and the 20 pin 82 upon the front jaw 80 is brought alternately against the shoulder 99 and the pawl 100, in order to bring the back jaws into alignment with the front jaws as the strand 25 of rattan is transferred from one to the other. 30

103 denotes a blade-spring bent around the ends of the back jaws, with its tension applied to the back jaws to carry them toward each other during the swinging movement of the lever 61 until stopped by the pin 104 in the 35 jaw 91 coming in contact with the inner side of jaw 90.

The needle 26 consists of a straight cylindrical bar attached to the arm 25 upon the slotted plate 23, which is actuated by the 35 crank-pin 21. The upper end of the needle is illustrated in Figs. 13 and 13^a, and is provided with a shoulder 105, which is brought against the lower end of the sliding block 50 as the needle is moved upward, causing the 40 block 50 to be slid upward upon the post 46. The tip of the needle is beveled at 106 to allow it to slide readily under the blade-spring 49 and lift it from the post or stud 54, thereby releasing the sliding block 50. To the 45 needle is pivoted a sharp-pointed wheel 107, the ends of the teeth being adapted to indent but not to cut the strand of rattan.

108 denotes a tube extending from the upper side of the case 2 downward through the table 50 1, through which a continuous strand of rattan is passed, taken from a spool placed in any convenient position outside the machine, and not shown in the drawings. At its upper end the tube 108 is parallel with and close 55 beside the needle 26, as shown in Fig. 3, and in larger view in Figs. 9 and 12, and the strand of rattan is conducted from the upper end of the tube 108 to a strand-holder 109 attached to the upper side of the case 2 upon 60 the opposite side of the needle. The strand-holder consists of a plate with the two vertical walls 110 110 extending upward and inclosing a space between them equal to the diameter of the strand of rattan through which the 65 strand is carried, the section of the strand between the upper end of the tube 108 and the

strand-holder being directly over the toothed wheel 107 upon the needle 26.

The method of forming a loop by the action of the mechanism above described is as follows: The strand of rattan is conducted through the tube 108 and through the space between the vertical walls 110 110 of the strand-holder with the needle at its lowest position, as shown in Fig. 9, and with the sliding block 50 at its lowest position on the post 46, the tongue 51 in a horizontal position at right angles with the post 46, the blade-spring 49 resting upon the stud 54, with the pin 55 entering a hole in the spring 49. The lever 61 is held in the position shown in Fig. 1, with one of the loop-holders between the walls 71 71 upon the loop-former and with the loop-former and arm 84 rocked upon their pivotal pins so as to carry the jaws forward, bringing 85 the strand of rattan under the front jaws 80 81. The needle 26 is then moved upwardly, bringing the toothed wheel 107 in contact with the strand of rattan, carrying it upward between the walls 71 71 and forming a loop 72, Figs. 9c 10 and 12, the beveled tip 106 of the needle, pushing the tongue 51 up and passing beneath the blade-spring 49, lifts it off the stud 54, releasing the sliding block 50, which is pushed up the post 46 by means of the shoulder 105 95 coming in contact with the foot of the block, the pawl 53 engaging a projecting shoulder 112 attached to the ring 30, thereby holding the sliding block from moving downward as the needle is moved down. As the needle is 100 moved down, leaving the loop 72 standing in the position shown in Fig. 12, the blade-spring 49, as it is released by the removal of the needle, will rest upon the tongue, as shown in Fig. 7, carrying the loop toward the post 46 105 and into the groove 58 of the tongue 51.

During the formation of the loop 72, as described, the front and back jaws occupy the position shown in plan view in Fig. 16, with the pin 82 against the pawl 100 opening the back 110 jaws against the tension of the blade-spring 103 and holding the back jaw 91 in alignment with the front jaw 80 and the back jaw 90 in alignment with the front jaw 81 and with the strand 111 extending from the tube 108 over 115 the end of the needle 26 and beneath the front jaw 81. A loop having been formed while the ring 30 is held at rest by the teeth 40 of the sliding locking-bar 39, and the needle 26 having been moved down to its lowest 120 position, the ring 30 is moved by means of the feeding mechanism actuated by the cams 7 and 11, bringing the next successive loop-holder over the needle, the loop-former 65 moving with the loop-holder by means of the 125 link 62. As the pin 82 moves away from the pawl 100 the back jaws are moved toward each other until the stop-pin 104 is brought in contact with the back jaw 90, as shown in Fig. 17, and at the limit of the feeding motion of the loop-former the pin 82 is brought 130 against the shoulder 99 upon the back jaw 90,

pressing the back jaws apart against the tension of the spring 103 and bringing the back jaw 90 in alignment with the front jaw 80, when the front and back jaws are moved back 5 by means of the actuating-cam 17 and intermediate operating mechanism rocking the loop-former 65 and arm 84 simultaneously and carrying the back jaw 90 over the strand of rattan 111, as shown in Fig. 18. The back- 10 ward rocking motion of the front and back jaws serves to bring the walls 71 71 clear from the loop-holder, as shown in Fig. 18, allowing the lever 61 to be moved back by means of the reverse motion of the rack 10, bringing 15 the walls 71 71 opposite the loop-holder which has been brought over the needle, carrying the pin 82 away from the shoulder 99, permitting the jaws 90 91 to be again brought toward each other, as shown in Fig. 19, until the 20 pin 82 is again brought against the pawl 100, and by its pressure against the pawl opening the back jaws, carrying the jaw 90 into alignment with the front jaw 81, the jaw 90 serving to hold the strand down between the walls 25 110 110 of the strand-holder and in the plane of the front jaw 81, when the front and back jaws are again rocked forward, bringing the front jaws 80 81 over the strand of rattan, as shown in Fig. 16, and in position for the next 30 loop to be formed, in the manner already described.

The successive movements of the mechanism described above for forming the loops occur in the following order: The needle 26 moves upward, carrying the strand between the vertical walls 71 71 and drawing it through the tube 108, bending the strand around jaw 81 and also around the toothed wheel 107, forming a loop 111, which is held by the loop-holder as the needle moves down. When the needle has moved downward, the ring 30 is moved forward in order to bring the next succeeding loop-holder over the needle, the loop-former 65 moving with the ring, which is necessary, for the reason that the recently-formed loop 111 held upon the loop-holder is still between the vertical walls 71 71. As the ring 30 and loop-former 65 move forward, the pin 82, which projects from the face of the jaw 80, is carried from its contact with the pawl 100 and brought into contact with the jaw 90, the pressure of the pin 82 against the jaw 90 serving to rock the jaws 90 91 on their pivots 92 93 and separate the jaws against the tension of the spring 103, holding the back jaw 90 in alignment with the front jaw 80. A simultaneous swinging motion of the loop-former 65 and arm 84 now takes place, carrying the loop-former back to release the recently-formed 60 loop and carrying the back jaw 90 over that portion of strand which extends from the recently-formed loop to the tube 108. The jaw 90 now serves to hold the strand down while the loop-former is rocked upon the pivot 59 65 in order to bring the loop-former opposite the next loop-holder, which has been brought over the needle by the intermittent movement of

the ring 30, at the same time bringing the pin 82 against the pawl 100, causing the jaws 90 and 91 to be opened so the jaw 90 will be 70 brought into alignment with the front jaw 81. The loop-former 65 and arm 84 are then simultaneously swung forward, carrying the jaw 90 off the strand and bringing the jaw 81 to occupy the same position over the strand 75 and bringing the vertical walls 71 71 into position for the next succeeding loop to be formed by the upward movement of the needle. The office of the back jaw 90 is to hold the strand down between the walls 110 110 80 during the backward swinging movement of the loop-former, and the office of the jaw 91 is to act as a bell-crank when actuated by the pin 82 to swing the jaw 90 and bring it into alignment with the jaw 81, in order that when 85 the loop-former 65 and arm 84 are swung forward the strand may be transferred from the under side of the jaw 90 to the under side of the jaw 81. A series of loops are thus formed upon the successive loop-holders, each loop 90 being held upon the grooved tongue 51 of the loop-holder which is held in a vertical position by the tension of the spring 49, the raised portion 56 of the tongue entering the recess 57 in the sliding block 50, which is held up 95 by means of the pawl 53 engaging the shoulder 112. The loop-holders are maintained in a position with their posts 46 parallel with the side of the ring 30 by means of a band 114 extending around the ring 30 and supported 100 upon brackets 115 attached to the arched stand 27. The band 114 is, however, deflected from its position parallel with the ring 30, upon the left side of the machine, as indicated at 116, Fig. 2, and between the deflected portion of the band 114 and the ring 30 is interposed a plate 117, with its outer edge forming a cam-slot 118, through which the upper ends of the posts 46 of the loop-holders are carried as the ring 30 is rotated. By means of the 110 cam-slot 118 the posts 46, as they pass through the slot, are raised from a position parallel with the ring 30 to an oblique position thereto, causing the pawls 53 to be carried off the projecting shoulders 112 and allowing the sliding blocks 50 to be moved down the posts 46 and bringing the tongues 51, together with the loops carried upon them, into a position at 115 right angles with their posts 46. As the loop-holders are carried from the cam-slot 118 into 120 that portion of the band 114 parallel with the ring 30 the posts are again brought parallel with the ring 30 and with the tongues 51 in a horizontal position as they are inclosed by the loop-former 65 in its forward rocking movement, as above described, the loop held upon the tongue entering the mortise 79 in the loop-former, which maintains the loop in a horizontal position as a new loop is formed. After one set of loops have been formed the 125 130 second series of loops will be placed within the first series, the needle as it carries the strand of rattan upward to form the loop passing through the horizontal loop held upon

the tongue 51, pushing the tongue up, as described above, while the loop upon the tongue is held in its horizontal position by means of its entering the mortise 79.

5 In Fig. 12 the portion of the horizontal loop held upon the tongue is shown at 119 in sectional view, and in Figs. 16 to 19, inclusive, the horizontal loops are indicated by broken lines 120.

10 The sliding blocks 50 are drawn down and the tongues 51 brought into a position at right angles to the posts 46 by means of the withdrawing mechanism comprising a disk 121, capable of rotating upon a stud 122 attached

15 to and projecting horizontally from the rear side of the case or shell 2. Pivoted within radial slots in the disk 121 are a series of radial arms 123, with a series of links 124 pivoted to their outer ends, the free ends of the

20 links 124 having hooks 125 adapted to engage the loops in the knit fabric as it leaves the knitting mechanism, as described. Attached to the case or shell 2, or to a fixed part of the machine, is a plate 126, curved concentrically

25 with the axis of the disk, with its edge 127 presenting a cam-surface to the radial arms 123, and by which the arms are pushed back as they pass over the inclined portion at 128.

129 is a collar attached to the end of the 30 stud 122, serving to hold the disk 121 upon the stud and having the radial arms 130, to which is attached the cam-plate 131, its edge 132 forming an opposing cam-surface to the edge 127 of the plate 126, the inclined surface 133, Fig. 31, serving to push the arms 123 forward toward the knitting mechanism.

35 Mounted upon and attached to the curved cam-plate 126 is a cam-plate 134, its edge 135 acting as a cam to raise the links 124 as they 40 pass over it and bring their hooked ends up and into the loops of the knit fabric. The number and position of the radial arms 123 and their hooked links 124 correspond with the loop-holders 41 upon the ring 30, and an

45 intermittent rotary motion is imparted to the disk 121 simultaneous with the intermittent rotary motion of the ring 30 by means of a feeding mechanism, (shown in Fig. 5, and in rear view in Fig. 4^a), and comprising a gear-

50 wheel 136 attached to or formed integrally with the disk 121, as illustrated partly in the sectional view in Figs. 20 and 21, a three-armed lever provided with the arms 137, 138, and 139, having a rocking motion upon a stud

55 140 held in the case 2, and actuated by means of a link 137^a, connecting the arm 137 with the radial arm 12 on the rocking shaft 13. The arms 138 and 139 are connected, respectively, with a lever 141, pivoted upon a stud 142, held

60 in the case 2 and having a tooth 143, and with link 144 provided with a rack 145.

By means of the rocking motion of the three-armed lever the lever 141 and link 144 are rocked upon their pivots, and the teeth of 55 the rack 145 and the tooth 133 are alternately made to engage the teeth of the gear-wheel 136.

The link 144 is pivoted to a vibrating lever

146, pivoted at its center upon a stud 147, held in the case 2 and actuated by a link 148, connecting the end of the lever 146 with the lever 8, which is actuated by the cam 7. A reciprocating motion is thus given to the rack 145 corresponding to and simultaneous with the reciprocating motion of the rack 10. The arm 139 of the three-armed lever is connected 75 with the link 144 by means of a stud 149, held in the end of the arm 139 and journaled in a block 150, having a sliding motion in a slot 151 in the link 144. When the rack 10 is moved toward the left, Fig. 5, with its teeth 80 in mesh with the teeth 36 of the ring 30, the lever 144 is also moved toward the left, Fig. 5, and the rack 145 is at the same time raised to engage the teeth of the gear-wheel 136 by the rocking motion of the three-armed lever, 85 which is caused to simultaneously lower the lever 141, removing its tooth 143 from the teeth of the gear-wheel 136, allowing the gear-wheel and connected disk 121 to be rotated a space equal to the distance from the center 90 of one of the radial arms 123 to the center of the next adjacent arm and causing the radial arms 123 to be carried around the stud 122 synchronously with the rotation of the loop-holders 41 around an axis coincident with the 95 axis of the stud 59. The rocking motion of the three-armed lever is then reversed, bringing the rack 145 out of engagement with the teeth of the gear-wheel 136 and carrying the end of the lever 141 upward, causing the tooth 100 143 to engage the teeth of the gear-wheel and securely locking it against any movement as the motion of the rack 145 is reversed.

As the several series of loops are formed by the loop-forming mechanism, they are delivered therefrom in the form of a continuous circular fabric, a portion of which is indicated by the broken links 120, Figs. 16 to 19, surrounding the hooked links 124 and being rotated as the ring 30 is rotated, simultaneously 110 with the rotation of the hooked links 124. Each of the radial arms 123, as it is carried down by the rotation of the disk 121, is forced forward by the action of the inclined edge 133 of the cam-plate 130, and as the links 124 pass 115 around the lower portion of their path they will rest by their own gravity upon the knit fabric, with their hooked ends engaging the loops of the fabric. In the passage of the radial arms upward from the lower to the higher 120 portion of the circle they are pushed back by the inclined edge 128 of the cam-plate 126, drawing the loops of the knit fabric taut as the posts 46 are being raised away from the ring 30 by means of the cam-plate 117. Each 125 of the radial arms 123 is pushed farther back as it and its corresponding loop-holder approaches the loop-forming mechanism by means of a sliding plunger 152, Figs. 1 and 2, held in a bracket 153, attached to the side of 130 the case 2 and actuated by means of a bell-crank having arms 154 and 155 and pivoted on a stud 156, held in the case 2. The bell-crank lever is rocked upon its pivot simul-

taneously with the upward motion of the needle 26 in forming a loop by means of a pin 157, projecting through a slot 158 in the case 2 from the slotted plate 23, Fig. 3, which is 5 actuated by the crank-pin 21.

In Fig. 2 the pin 157 and bell-crank lever are shown in their position at the beginning of the upward motion of the slotted plate 23. As the bell-crank is raised the arm 155 is 10 brought against the end of the sliding plunger 152, pushing it endwise against the radial arm 123, at that time opposite the plunger, carrying the arm back and by means of its connected hooked link drawing the loop engaged 15 by the hook rearward, sliding the block 50 upon the corresponding loop-holder down upon its post 46, and also bringing its tongue from a position parallel with the post to a position at right angles thereto. This action of 20 the sliding plunger 152 is more fully illustrated in Figs. 20 and 21, the first denoting the relative position of the parts concerned in the operation of withdrawing the loops before the action of the sliding plunger 152 and 25 the latter after the radial arm has been pushed back. The construction of the sliding plunger 152 is also illustrated in Figs. 20 and 21, the plunger consisting of a hollow tube, which slides in the bracket 153 and is sur- 30 rounded by a retractile spring 159, inclosed in an annular chamber and acting against a shoulder 160 in the bracket, and a shoulder 161 on the sliding tube 152. Within the tube 152 is held a rod 162, provided with a shoul- 35 der 163 and carrying a spring 164, acting against the shoulder 163 and the end of the tube 152. A pin 165 in the rod 162 enters the slot 165^a in the tube 152, and causes the rod 162 to be carried with the tube 152 when 40 it is withdrawn by the retractile spring 159, and another pin 166 is held in the bracket 153 in the path of the shoulder 161 to limit 45 the motion of the tube in the bracket.

The spring 164 is inserted in the mechanism for the purpose of allowing the rod 162 to yield in case of any undue resistance, thereby avoiding the breakage of the operating parts, which are actuated by the plunger, and the spring is therefore made of sufficient 50 strength to transmit whatever force is ordinarily required to move the block 50 down and withdraw the tongue 51.

It will be observed that the cam-plate 117 not only raises the post 46 of the loop-holder 55 away from the ring 30, so as to release the pawl 53 from the shoulder 112, but it also reduces the angle between the post 46 upon which the block 50 slides and the line of draft exerted by the hooked link 124, thereby facil- 60 itating the movement of the block 50 and tongue 51.

The loop-holders as they pass around toward the loop-forming devices are made to again assume a vertical position by means of 65 the band 114, and the sliding block 50 is locked down by means of the pin 55 entering a hole in the blade-spring 49. After the first

series of loops have been formed upon the tongues, the second series are formed in the same manner, each loop of the second series 70 being pushed up through a loop of the first series represented at 119 in Figs. 9 and 12, each series of loops becoming locked in the series immediately preceding.

As the back and front jaws are brought 75 into alignment with each other, as shown in Figs. 16 and 18, for the purpose of transferring the strand from one to the other, the front jaws are made to overlap the upper surface 80 of the back jaws, so that any upward strain 85 upon the back jaws is received by the front jaws. The loop-former 65 carries the plate 70, which is provided with a circular notch 168, in which the raised portion 56 of the tongue rests while the loop is being made by 90 the action of the needle, bringing the horizontal loop held upon the tongue in position to enter the mortise 79 and be thereby held from being lifted by the needle and the new loop being formed within the horizontal loop. 95 The walls 71 71 are also carried up far enough to inclose each side of the vertical loop as it is left by the needle, thereby preventing it from spreading laterally, the sides of the loop being held by the vertical walls, as shown at 100 169, Fig. 12. The strand of rattan is conducted to the knitting mechanism through a tube 108, parallel with and at the side of the needle, so the action of the needle in forming a loop is enabled to feed the strand by drawing it directly through the tube. The toothed wheel 107 as it runs along upon the inner surface of the loop indents the fiber upon the surface, as illustrated in Fig. 33, thereby shortening the fiber upon the inside, removing 105 the strain upon the strand incident to bending, and preventing the splitting of the strand at the convex sides 169 of the loop.

Although the fabric as produced by our improved machine is similar to what is known as 110 "plain" knitting, being a series of loops simply interlaced, the refractory character of the strand of rattan requires in many respects a mechanism entirely unlike that employed in the process of knitting ordinary textile fabrics, in which the tension upon the thread to 115 be knit is made to accomplish what in our machine is effected by devices operating upon the strand of rattan during the entire process of knitting; and although the method of 120 forming a loop by means of a reciprocating needle, with its attendant devices for retaining the strand and for holding the loop already formed, were shown substantially in the machine forming the subject of Letters Patent 125 No. 299,295, granted to us May 27, 1884, the conditions of knitting a continuous circular fabric are so varied as to demand many essential modifications of the operating parts, as 130 therein shown.

The circular fabric when knit by our improved machine is cut apart lengthwise and spread out in a plane surface, and being cut into pieces of the requisite size is stretched

upon and fastened to the furniture-frame, as shown in Fig. 30. The strand-tube 108 is screwed at its upper end into the shell or case 2 and its lower end receives a tube 172 into 5 a funnel-shaped opening 173. The diameter of the tube 108 is nearly the size of the strand of rattan and serves to hold the strand from lateral displacement on one side of the needle 26, while the parallel walls 110 110 retain the 10 strand upon the opposite side of the needle, as illustrated in Fig. 24.

Fig. 25 shows one of the links by which the jaws are rocked as disengaged from the stud 78 in the lever 18, permitting the jaws to be 15 separated if for any reason it is desired to do so. The rocking motion of the front and back jaws being simultaneous while the machine is in operation, the pin 82 is always held between the jaws 90 91, traversing from 20 contact with the shoulder 99 to contact with the pawl 100, and vice versa; but in case the jaws are ever separated by means of either of the links 77 87 becoming disengaged from the stud 78 and the pin 82 brought to 25 the left of the pawl as the front jaws are carried upon the lever 61, the pawl will yield upon the return movement of the pin 82 and allow it to pass between the back jaws. To 30 the rectangular collar 47 we attach a slotted blade 171, inclosing the pin 52, by which the sliding block is held from being moved too far down the post 46, in case it is not caught by the pin 55 entering the hole in the blade-spring 49. The action of the hooked links 35 124 is shown in the diagrammatic Figs. 26 to 29.

In Fig. 26, 174 indicates the relative position of the loop as held upon the tongue and as left by the reciprocating needle. 175 and 40 176 are loops in the knit-fabric, and 124 shows one of the hooked links engaging the loop 176. This is the position occupied by the link 124 at the top of its circular path and as the loop is being formed by the needle 26. 45 As the link passes to the right, Fig. 1, the arm to which it is pivoted is moved forward, and as the link passes around the lower part of its circular path it falls into loop 175, Fig. 27. As the radial arm and connected hooked link 50 passes up the left side it is pushed back by the cam 126, drawing the hook 125 into the loop 175, as shown in Fig. 28. When the radial arm and connected link reach a point opposite the sliding plunger 152, the actuating 55 mechanism forces the plunger against the arm and pulls the knit fabric backward, the loop 174, which is held upon the tongue of the loop-holder, assuming the position shown in Fig. 28 by reason of the inclination of the 60 loop-holder as it is raised by the cam 117, and in Fig. 29 the loop held upon the tongue is shown as having been drawn into a horizontal position ready for a new loop to be pushed through it by the action of the reciprocating 65 needle.

We prefer to corrugate the jaw 81, as shown at 81^a in Fig. 32, in order to slightly in-

dent the strand of rattan as it is bent around the jaw by the reciprocating needle 26, for the same reason as the loop is slightly indented by the toothed wheel 107. Fig. 33 70 illustrates the indentations of the strand of rattan, that formed by the jaw 81 being shown at 177 and that formed by the toothed wheel 107 at 178, the fabric represented in Fig. 33 75 being the same as that forming the subject-matter of Letters Patent No. 472,320, issued to Edward L. Taft, April 5, 1892.

What we claim as our invention, and desire to secure by Letters Patent, is— 80

1. The combination of a prong or jaw serving as a fulcrum around which the strand is bent in forming the loop; a reciprocating needle and a toothed wheel pivoted on said needle by which the surface of the strand is indented, substantially as described. 85

2. The combination with the mechanism for forming a loop of the strand of rattan, comprising in its essential features devices for holding the strand from lateral displacement, 90 a reciprocating needle, and a prong or fulcrum around which the strand is bent, of a toothed wheel pivoted upon said needle and provided with a series of teeth adapted to slightly indent the surface of the strand of 95 rattan as the strand is being bent by the action of the reciprocating needle, substantially as described.

3. The combination with a prong or jaw around which the strand of rattan is bent as 100 a fulcrum and a reciprocating needle, of a strand tube 108 contiguous to and parallel with said reciprocating needle, through which the strand of rattan is conducted, substantially as described. 105

4. The combination with a prong or jaw serving as a fulcrum about which the strand of rattan is bent and a strand tube through which the strand of rattan is conducted, of a reciprocating needle and a wheel pivoted 110 upon said needle, said wheel being provided with teeth adapted to slightly indent the surface of the strand of rattan, as the loop is being formed by the action of the reciprocating needle, substantially as described. 115

5. The combination with a prong or jaw serving as a fulcrum about which the strand of rattan is bent and a reciprocating needle, of a pair of parallel walls 71 71 inclosing the 120 sides of the loop as formed by the action of said reciprocating needle, whereby the loop is held laterally, substantially as described. 125

6. The combination of a ring or frame for supporting a series of loop-holders, posts 46 hinged to said ring or frame, a block sliding 130 on said post, a tongue 51 hinged on said block, spring 49, means as described for holding the strand during the formation of the loop, a pawl pivoted on said sliding block, a shoulder projecting from said ring or frame a reciprocating needle by which said block is moved on said post, and a pawl spring by which said pawl is made to engage said projecting shoulder, substantially as described. 135

7. The combination of sliding block 50, provided with a transverse recess 57, a loop-holding tongue having a raised portion 56 entering said recess when the tongue is raised a reciprocating needle by which said tongue is raised and loop former 65 provided with the curved notch 168 fitting the edge of the curved portion of said tongue, and a mortise 79, substantially as described.

8. The combination of post 46, sliding block 50 having a stud 54 and pin 55, and a blade spring 49 fixed to said post and provided with a hole to receive the pin 55 and thereby retain the sliding block in its lowest position, substantially as described.

9. The combination of post 46, sliding block 50 carrying a loop-holding tongue, pin 52 projecting from said sliding block and slotted plate 171 fixed to said post, substantially as described.

10. The combination of jaw 81 around which the strand of rattan is bent, a reciprocating needle, parallel walls 110, 110 placed beneath said jaw 81, and a strand tube 108 parallel with said needle, substantially as described.

11. The combination of a ring provided with teeth and a reciprocating rack-bar engaging said teeth, an actuating cam by which said rack-bar is moved, a series of loop-holders attached to said ring and arranged radially thereon and a reciprocating needle, placed in a plane parallel with said ring, a rotating crank and connecting mechanism whereby said needle is actuated radially to said ring as the several loop-holders are brought into alignment with said needle, and the loop former 65, substantially as described.

12. The combination with a ring having a series of loop-holders hinged thereto, and arranged radially upon the side of said ring, of the band 114 provided with an off-set 116 but otherwise placed with its edge parallel with the side of said ring, by which the loop-holders are held against the side of the ring, substantially as described.

13. The combination with a ring supporting a series of loop-holders, of a series of loop-holders arranged radially upon the side of said ring, a reciprocating rack bar engaging said ring, an actuating cam by which said rack bar is moved, a lever pivoted upon a stud coincident with the axis of said ring, a loop-former 65 pivoted upon said lever, said lever being connected with said reciprocating rack bar by which said lever is given an oscillating angular motion corresponding with the intermittent motion of said ring and said loop-former being capable of an angular motion in a plane at right angles with the plane of said ring, and connected operating mechanism for imparting said angular motion to said loop-former, substantially as described.

14. The combination with mechanism for holding the loops, substantially as described and a reciprocating needle by which the strand of rattan is bent and carried upon said loop-holding mechanism, of a rotating crank and

connecting mechanism by which said needle is actuated, the loop-former 65 provided with jaws 80, 81, arm 84 carrying jaws 90, 91, said jaws capable of an oscillating motion about coincident axes, whereby the strand of rattan is transferred from the jaws 80, 81 to the jaws 90, 91 and vice versa, and connected means for imparting an oscillating motion to said loop former and said arm 84 substantially as described.

15. The combination of a ring a reciprocating rack-bar engaging said ring and actuating cam by which said rack-bar is moved, pivoted lever 8 and means, as described by which said rack bar is carried into and out of engagement with said ring, a series of loop-holders attached to said ring and arranged radially thereon a loop-former, a reciprocating needle placed in a plane parallel with said ring a rotating crank and connecting mechanism by which said needle is moved radially to said ring and a strand tube through which the strand of rattan is conducted, substantially as described, said strand tube being parallel with said needle.

16. The combination of a ring a toothed rack-bar engaging said ring, an actuating cam by which said rack-bar is reciprocated, pivoted lever 8 and means as described, by which said rack bar is carried into and out of engagement with said ring a series of loop-holders attached to said ring and arranged radially thereon, a loop-former a reciprocating needle placed in a plane parallel with said ring a rotating crank and connecting mechanism whereby said needle is moved radially to said ring, and a toothed wheel pivoted on said needle, whereby the strand of rattan is slightly indented, substantially as described.

17. The combination with a ring provided with teeth, a reciprocating rack-bar engaging said teeth, an actuating cam by which said reciprocating rack-bar is moved pivoted lever 8 and means, as described, by which said rack bar is carried into and out of engagement with said ring and a series of loop-holders arranged radially thereon, a loop-former of a reciprocating needle by which the strand of rattan is bent into a loop and carried upon said loop-holders, a rotating crank and connecting mechanism by which said needle is moved and a pair of vertical walls 110, 110, inclosing the strand of rattan and holding it from lateral displacement as the loop is formed, substantially as described.

18. The combination with a ring provided with teeth, a reciprocating rack-bar engaging said teeth, an actuating cam by which said reciprocating rack-bar is moved pivoted lever 8 and means as described, by which said rack bar is carried into and out of engagement with said ring and a series of loop-holders arranged radially on said ring, of a loop-former a reciprocating needle by which the strand of rattan is bent into a loop and carried upon said loop-holders, a rotating crank and con-

necting mechanism by which said needle is moved a toothed wheel pivoted upon said needle, whereby the strand of rattan is slightly indented, and a pair of vertical and parallel walls inclosing the strand of rattan and holding it from lateral displacement substantially as described.

19. The combination with a ring having a series of loop-holders, arranged radially thereon said ring being provided with teeth, a reciprocating rack-bar engaging said teeth and an actuating cam by which said reciprocating rack-bar is moved, of the loop-former, a reciprocating needle, a rotating crank and connecting mechanism by which said needle is moved a toothed wheel pivoted upon said needle, a pair of vertical and parallel walls inclosing the strand of rattan, and a strand tube parallel with said reciprocating needle, pivoted lever 8 and means, as described, by which said bar is carried into and out of engagement with said ring all arranged substantially as described.

20. The combination with mechanism for holding the loops, substantially as described, and a reciprocating needle for bending the strand of rattan, of a rotating crank and connecting mechanism for actuating said needle the front jaws 80, 81, back jaws 90, 91 and a pair of parallel walls inclosing the strand of rattan, said front and back jaws being capable of simultaneous rocking motion about coincident axes, and means for imparting a rocking motion to said jaws substantially as described.

21. The combination with mechanism for holding the loops, substantially as described and a reciprocating needle for bending the strand of rattan, of a rotating crank and connecting mechanism for actuating said needle the front jaws 80, 81, back jaws 90, 91, said jaws being capable of a simultaneous rocking motion about coincident axes, and means, as described, for imparting a rocking motion to said jaws a pair of parallel walls inclosing the strand of rattan and a strand tube through which the strand of rattan is conducted to the needle, substantially as described.

22. The combination with mechanism for holding the loops, substantially as described and a reciprocating needle for bending the strand of rattan, of a rotating crank and connecting mechanism by which said needle is actuated the front jaws 80, 81, back jaws 90, 91, said jaws being capable of a simultaneous rocking motion about coincident axes, and means, as described, for imparting a rocking motion to said jaws a pair of parallel walls inclosing the strand of rattan, and a toothed wheel pivoted on said reciprocating needle, whereby the strand of rattan is slightly indented, substantially as described.

23. The loop-former 65 with its jaws 80, 81, arm 84 with its jaws 90, 91, said arm and loop-former having a rocking motion about coincident axes, lever 73 connected with the loop-former, lever 86 connected with the arm 84,

links 77 and 87 oscillating lever 18 and actuating cam 17, all combined substantially as described.

24. The loop-former 65 with its jaws 80, 81, arm 84 with its jaws 90, 91, said arm and loop-former being capable of a rocking motion about coincident axes, lever 73 connected with the loop-former, lever 86 connected with the arm 84, links 77 and 87, oscillating lever 18, actuating cam 17 and a series of loop-holders arranged radially upon the side of a ring, a ring carrying said loop-holders and having an intermittent rotary motion, connected actuating mechanism consisting of a rack-bar engaging said ring and a cam by which a reciprocating motion is imparted to said rack-bar pivoted lever 8 and means by which said rack bar is carried into and out of engagement with said ring all combined substantially as described.

25. The loop-former 65 with its jaws 80, 81, arm 84 with its jaws 90, 91, lever 73 connected with the loop-former, lever 86 connected with the arm 84, links 77 and 87, oscillating lever 18, actuating cam 17, loop holding mechanism substantially as described, a reciprocating needle by which the strand of rattan is bent, a rotating crank and connecting mechanism by which said needle is actuated all combined, substantially as described.

26. The loop-former 65 with its jaws 80, 81, arm 84 with its jaws 90, 91, lever 73 connected with the loop-former, lever 86 connected with the arm 84, links 77 and 87, oscillating lever 18, cam 17, loop-holding mechanism, substantially as described, a reciprocating needle by which the strand of rattan is bent a rotating crank and connecting mechanism by which said needle is actuated and a toothed wheel pivoted upon said needle by which the surface of the strand is slightly indented, all combined substantially as described.

27. The combination of loop-former 65 with its jaws 80, 81, arm 84 with its jaws 90, 91, lever 73 connected with the loop-former, lever 86 connected with the arm 84, links 77, and 87, oscillating lever 18, cam 17, loop-holding mechanism, substantially as described, a reciprocating needle by which the strand of rattan is bent, a rotating crank and connecting mechanism by which said needle is actuated a toothed wheel pivoted upon said needle, and a pair of parallel walls inclosing the strand and holding it from lateral displacement as the jaws are oscillated, substantially as described.

28. The loop-former 65 with its jaws 80, 81, arm 84 with its jaws 90, 91, lever 73 connected with the loop-former, lever 86 connected with the arm 84, oscillating lever 18 provided with a stud 78, actuating cam 17, links 77 and 87 provided with hooks adapted to engage the stud 78 and arms 75 and 88, all combined substantially as described.

29. The combination of actuating cam 17, oscillating lever 18, link 77 provided with a slot 76 and having a sliding motion in the arm

89 attached to the rigid part of the machine, oscillating loop-former 65 pivoted upon a lever 61, lever 61 having a rocking motion in a plane at right angles to the plane of the oscillation of the loop-former, and lever 73 connected with the loop-former and carrying a stud 74, having a transverse and longitudinal sliding motion in the slot 76 of the link 77, whereby the operative connection is maintained between the link 77 and the lever 73, substantially as described.

30. The combination of the back jaws 90, 91 pivoted at 92, 93, spring 103 applied to bring said jaws together, front jaws 80, 81 one of said front jaws having a pin 82 projecting between opposing shoulders upon the back jaws, by which the back jaws are brought into alignment with the front jaws at each end of the traversing movement of said front jaws, substantially as described.

31. The combination of the back jaws 90, 91 having arms 94, 95 so connected that a vibrating motion of one of said jaws will produce a similar vibrating motion of the other jaw, but in the opposite direction, spring 103 applied to said jaws to bring them together, and front jaws 80, 81, one of said front jaws having a pin 82 projecting between said back jaws, whereby said back jaws are brought into alignment with said front jaws at each end of the traversing motion of the front jaws, substantially as described.

32. The combination of back jaws 90, 91 pivoted at 92, 93 and having arms 94, 95 operatively connected, substantially as described, spring 103, applied to bring the back jaws together, stop pin 104, by which the inward movement of the jaws is limited, and front jaws 80, 81, one of said front jaws having a pin 82 projecting between said back jaws, whereby the back jaws are brought into alignment with said front jaws, substantially as described.

33. The combination of arm 84 pivoted upon a bracket 83, bracket 83 attached to the rigid portion of the machine, back jaws 90, 91 pivoted upon the arm 84, spring 103 applied to bring the back jaws together, lever 61 having an angular motion upon a stud 59, means as described for actuating said lever loop-former 65 pivoted in the lever 61 with its axis coincident with the axis of the arm 84 and having jaws 80, 81, and pin 82 projecting between the back jaws and alternately brought into contact with each of said jaws as the lever 61 is oscillated upon the stud 59, thereby bringing said back jaws into alignment with the jaws 80, 81, substantially as described.

34. The combination of the loop-former 65 provided with front jaws 80 and 81, one of said front jaws having a pin 82 projecting between the back jaws, an arm 84 provided with the back jaws 90 and 91 pivoted at 92, 93, spring 103, shoulder 99 and pawl 100 having a pawl spring 102, cam 17 and connecting mechanism by which said jaws are actuated, substantially as described.

35. The combination of a reciprocating needle by which the strand of rattan is bent into a loop, a rotating crank and connecting mechanism by which said needle is actuated a ring carrying a series of loop-holders arranged radially upon the side of said ring, said ring being provided with a "T" shaped slot, a ring supporting stand having roll supporting brackets and rolls held by said brackets and rolls 29^a supporting said ring, a reciprocating rack-bar engaging said ring and an actuating cam by which said rack-bar is moved and said ring and said reciprocating needle moving alternately pivoted lever 8 and means by which said rack bar is carried into and out of engagement with said ring substantially as described.

36. The combination of a ring having a series of loop-holders radially attached to its side and provided with circumferential teeth, a reciprocating rack engaging said teeth, an actuating cam by which said rack is moved, a pivoted lever connecting said rack and said actuating cam a sliding plate having a reciprocating motion radially to said ring and provided with ways in which said reciprocating rack is held, an actuating cam and connecting mechanism by which said sliding plate is moved, whereby said rack-bar is made to engage the teeth on said ring alternately and impart an intermittent rotating motion to said ring, substantially as described.

37. The combination with a ring provided with teeth and carrying a series of loop-holders, of a plate having a reciprocating motion radially to said ring, a rack sliding in ways on said reciprocating plate, and alternately engaging the teeth on said ring an oscillating lever actuated by said reciprocating plate, a sliding locking bar provided with teeth and operated in correspondence with the motion of said reciprocating plate and said sliding rack to lock said ring and hold it from rotation when said rack is disengaged from the ring, an actuating cam and connecting mechanism for moving said sliding plate and an actuating cam and connecting mechanism for moving said sliding rack substantially as described.

38. The combination of ring 30 carrying a series of radial loop-holders and provided with circumferential teeth, a sliding plate 15, rock shaft 13, arms 12 and 14 cam 11 sliding rack 10 and cam 7 with lever 8, substantially as described.

39. The combination of ring 30, provided with circumferential teeth and carrying a series of radial loop-holders, a sliding plate 15 having ways for a sliding rack, a sliding rack 10, lever 8, actuating cam 7, cam 11 rock shaft 13, arms 12 and 14 actuating said plate 15, lever 37, and sliding locking bar having teeth adapted to engage the teeth on said ring substantially as described.

40. The combination of ring 30 provided with circumferential teeth and carrying a series of loop-holders attached radially to

the side of said ring, a sliding plate 15 having a sliding motion in ways radially to said ring and being provided with ways for a sliding rack, a sliding rack 10, lever 8 operating 5 said rack, actuating cam 7, lever 61 pivoted concentrically with said ring a loop former 65 carrying strand holding jaws, and link 62, connecting said lever with the sliding rack, whereby the lever 61 is moved simultaneously with the intermittent motion of the 10 ring in one direction, rock shaft 13 with its radial arms 12 and 14 and actuating cam 11 by which an intermittent sliding motion is imparted to the plate 15, substantially as described.

41. The combination of ring 30 carrying a series of loop-holders, and being provided with circumferential teeth, actuating cams 7 and 11, oscillating lever 8, sliding rack 10 having teeth adapted to engage the teeth on said ring, lever 61 a loop former 65 carrying strand holding jaws, link 62 by which said lever is connected with said sliding rack, rocking shaft 13, having radial arms 12 and 14, sliding plate 15 provided with ways in which the sliding rack 10 slides, a reciprocating needle by which the strand of rattan is bent into loops, and connecting means for actuating said needle substantially as described.

42. The combination of ring 30 carrying a series of loop-holders and being provided with circumferential teeth, actuating cams 7 and 11, oscillating lever 8, sliding rack 10 having teeth adapted to engage the teeth on said ring, lever 61 a loop former 65 carrying strand holding jaws, link 62 by which said lever is connected with said sliding rack, rocking shaft 13, having radial arms 12 and 14, sliding plate 15 provided with ways for said sliding rack, 40 oscillating lever 37 actuated by said sliding plate 15, and sliding locking bar 39 having teeth adapted to engage the teeth in said ring and operated by said oscillating lever 37, substantially as described.

43. The combination of ring 30 carrying a series of loop-holders and being provided with circumferential teeth, actuating cams 7 and 11, oscillating lever 8, sliding rack 10 having teeth adapted to engage the teeth on said ring, lever 61 a loop former carrying strand holding jaws, link 62 by which said lever is connected with said sliding rack, rocking shaft 13 having radial arms 12 and 14, sliding plate 15 provided with ways for said sliding rack, 50 oscillating lever 37 actuated by said sliding plate 15, locking bar 39 operated by said sliding plate and oscillating lever and a reciprocating needle by which the strand of rattan is bent into loops, and connecting means by 55 which said needle is actuated substantially as described.

44. The combination with a ring carrying a series of loop-holders and provided with circumferential teeth, of a lever 61 pivoted upon 60 an axis concentric with the axis of the loop-holder carrying ring, a loop former 65 carrying strand holding jaws pivoted on said lever,

by arms 66, 67, strand holding jaws pivoted upon the arm 84, arm 84, pivoted upon a bracket attached to the rigid portion of the machine and upon an axis between the arms 66, 67 and coincident with the axis of said arms, actuating cam 7, pivoted lever 8 reciprocating rack 10, engaging the teeth upon said ring and operatively connected with said lever 61, by which said ring and lever are actuated simultaneously, actuating cam 17, and connecting mechanism by which said strand holding jaws are rocked upon their coincident axis substantially as described.

45. The combination with a ring carrying a series of loop-holders and provided with circumferential teeth, of a lever 61 pivoted upon an axis concentric with the axis of the loop-holder carrying ring, a loop former 65 carrying strand holding jaws pivoted upon said lever by arms 66, 67, strand holding jaws pivoted upon the arm 84, arm 84, pivoted upon a bracket attached to the rigid portion of the machine between the arms 66, 67 and upon an axis coincident with the axis of said arms, a reciprocating rack-bar operatively connected with said lever 61, and an actuating cam by which said reciprocating rack-bar is moved, pivoted lever 8 and means, as described, 95 whereby said rack bar is carried into and out of engagement with said ring an actuating cam and connecting operating mechanism by which said strand holding jaws are simultaneously rocked, and a reciprocating needle 100 by which the strand of rattan is bent into loops, and a rotating crank and connecting mechanism by which said needle is actuated substantially as described.

46. The combination of a ring carrying a series of loop-holders and provided with circumferential teeth, actuating cam 7, oscillating lever 8 and sliding rack 10, cam 11, rocking shaft 13 with arms 12 and 14 sliding plate 15 carrying said sliding rack, lever 61 a loop former 65 carrying strand holding jaws, link 62 connecting said lever with said sliding rack, an arm 84 carrying pivoted strand holding jaws and having a simultaneous rocking motion about a coincident axis, actuating cam 115 17, oscillating lever 18, links 77, 87, an intermediate connecting mechanism between said links and said jaws, substantially as described.

47. The combination of ring 30, loop holders carried by said ring, actuating cam 7, oscillating lever 8, sliding rack 10 having teeth engaging the teeth of the ring 30 at stated intervals, cam 11, rocking shaft 13, radial arms 12 and 14, plate 15 carrying the sliding rack 10, lever 37, sliding locking bar 39, lever 61 120 operatively connected with said sliding rack 10, a loop former 65 carrying strand holding jaws pivoted on said lever 61, strand holding jaws pivoted upon an arm 84, and an arm 84, pivoted upon a bracket attached to the stationary portion of the machine, actuating cam 17, oscillating lever 18, links 77 and 87, and levers 73 and 86, substantially as described.

48. The combination of ring 30 carrying a

series of loop-holders, actuating cam 7, oscillating lever 8, sliding rack 10, actuating cam 11, rocking shaft 13, radial arms 12 and 13, plate 15, oscillating lever 37, sliding locking bar 39, lever 61, operatively connected with said sliding rack 10, a loop former 65 carrying strand holding jaws pivoted on said lever 61 strand holding jaws pivoted on an arm 84, and an arm 84, pivoted on a bracket attached to the stationary portion of the machine, actuating cam 17, oscillating lever 18, links 77 and 87, levers 73 and 86, a reciprocating needle by which the strand of rattan is bent into loops, and a rotating crank and connecting mechanism by which said needle is actuated substantially as described.

49. The combination of ring 30 carrying a series of loop-holders actuating cam 7, oscillating lever 8, sliding rack 10, actuating cam 11 rocking shaft 13, radial arms 12 and 14, plate 15, oscillating lever 37, sliding locking bar 39, lever 61 pivoted upon an axis concentric with the ring 30, and operatively connected with said sliding rack 10, a loop former 65 carrying strand holding jaws and pivoted upon said lever 61, strand holding jaws pivoted upon an arm 84, and an arm 84, pivoted upon a bracket attached to the rigid portion of the machine, actuating cam 17, oscillating lever 18, arm 73, links 77, 87 arm 86, and a pair of parallel walls 110, 110, inclosing the strand of rattan and holding it from lateral displacement, substantially as described.

50. The combination of ring 30 carrying a series of loop-holders actuating cam 7, oscillating lever 8, sliding rack 10, actuating cam 11, rocking shaft 13 radial arms 12 and 14, sliding plate 15, oscillating lever 37, sliding locking bar 39, lever 61 pivoted upon a stud concentric with the ring 30, and operatively connected with said sliding rack 10, a loop former 65 carrying strand holding jaws and pivoted upon said lever 61, strand holding jaws pivoted upon an arm 84, and an arm 84, pivoted upon a bracket attached to the stationary portion of the machine, actuating cam 17, oscillating lever 18, arm 73 links 77, 87, arm 86, parallel walls 110, 110, for holding the strand of rattan from lateral displacement a reciprocating needle by which the strand of rattan is bent into loops, and a rotating crank and connecting mechanism by which said needle is actuated, substantially as described.

51. The combination of ring 30 carrying loop-holding mechanism, actuating cam 7, oscillating lever 8, sliding rack 10, actuating cam 11, rocking shaft 13, radial arms 12 and 14, sliding plate 15, oscillating lever 37, sliding locking bar 39, lever 61 pivoted upon a stud concentric with the ring 30, a link 62 connecting said lever 61 and said sliding rack, a loop former 65 carrying strand holding jaws having a rocking motion connected operating mechanism therefor, substantially as described, parallel walls for holding the strand of rattan from lateral displacement, a recip-

rocating needle by which the strand of rattan is bent into loops a toothed wheel pivoted upon said needle by which the surface of the strand is slightly indented, and connecting operating mechanism by which said needle is operated, substantially as described.

52. The combination with a ring 30 provided with projecting shoulders 112, of loop-holders comprising a post 46, sliding block 50, tongue 51, pawl 53 pivoted on said block, pawl spring 53^a and a stationary cam plate by which the posts of said loop-holders are raised, releasing the pawls from the projecting shoulders on said ring, substantially as described.

53. The combination of ring 30 posts 46 hinged to said ring, sliding blocks sliding on said posts, shoulders 112 on said ring, pawls 53 on said sliding blocks, tongues 51, and a stationary cam plate 117 by which the posts 46 are raised and the pawls 53 released from the shoulders 112, substantially as described.

54. The combination of ring 30, means for imparting an intermittent rotary motion to said ring posts 46 hinged upon said ring sliding blocks 50, pawls 53, shoulders 112 on said ring, stationary cam plate 117, and band 114, substantially as described.

55. The combination with a ring provided with projecting shoulders, of a series of loop-holders, substantially as described, upon which the successive loops of the knitted fabric are held pawls 53 engaging said projecting shoulders a cam plate 117 for raising said loop-holders at an oblique angle with said ring and a series of withdrawing hooks, arranged to engage the loops of the knitted fabric, and connected actuated mechanism substantially as described.

56. The combination of a ring means for imparting an intermittent rotary motion to said ring carrying a series of loop-holders, substantially as described, of a disk turning upon a stud held in the stationary portion of the machine concentrically with said rotating ring, connected actuating mechanism by which an intermittent rotary motion is imparted to said disk simultaneously with the motion of said ring a series of radial arms pivoted on said disk and a series of hooked links pivoted to said radial arms for engaging the loops of the knit fabric, substantially as described.

57. The combination of a ring means for imparting an intermittent rotary motion to said ring carrying a series of loop-holders, a disk turning upon a stud held in the stationary portion of the machine and concentrically with said rotary ring, and means for imparting an intermittent rotary motion to said disk a series of radial arms pivoted upon said disk, a series of hooked links pivoted to said radial arms for engaging the loops of the knit fabric, a cam plate placed concentrically with the axis of the rotating disk and presenting an inclined edge to said radial arms to force them toward the ring carrying the loop-hold

ers, and connected actuating mechanism by which the motion of said radial arms is reversed substantially as described.

58. The combination of a ring means for imparting an intermittent rotary motion to said ring carrying a series of loop-holders, a disk turning about an axis concentric with the axis of said ring, means for imparting an intermittent rotary motion to said disk, a series of radial arms pivoted on said disk, connected actuating mechanism by which said arms are carried toward said ring, a series of hooked links pivoted to the ends of said arms and a cam plate presenting an inclined surface to said arms to force them away from the ring carrying the loop-holders for the purpose of drawing the hooked links into the loops of the knit fabric, substantially as described.
59. The combination with a ring means for imparting an intermittent rotary motion to said ring, the ring carrying a series of loop-holders, a disk turning about an axis concentric with the axis of said ring, means for imparting an intermittent rotary motion to said disk a series of radial arms pivoted on said disk connected actuating mechanism by which said radial arms are moved toward and away from said ring, a series of hooked links pivoted to the free ends of said radial arms, and a cam plate arranged to lift said hooked links and carry them radially outward so their hooked ends will be held in the loops of the knit fabric, substantially as described.
60. The combination with a ring means for imparting an intermittent rotary motion to said ring, the ring carrying a series of loop-holders, a stationary cam plate held in the path of said loop holders, whereby they are raised at an oblique angle with said ring, a series of radial arms pivoted in a disk having an intermittent rotary motion about an axis concentric with the axis of said ring, means for imparting an intermittent rotary motion to said disk, a series of hooked links pivoted upon said arms and arranged to engage the loops of the knit fabric, together with connected operating mechanism, substantially as described, whereby the radial arms and connected hooked links are pushed back for the purpose of drawing the loops held upon the loop-holders from a plane at right angles with the axis of the rotating ring into a plane parallel thereto, substantially as described.
61. The combination of a ring means for imparting an intermittent rotary motion to said ring, a series of loop-holders arranged radially on said ring and hinged thereto, a stationary cam plate arranged in the path of said loop-holders by which they are raised into an oblique position to said ring, a series of radial arms pivoted to a disk having an intermittent rotary motion corresponding with the intermittent motion of said ring, means for imparting an intermittent rotary motion to said disk hooked links pivoted to the free ends of said radial arms and arranged to engage the loops

of the knit fabric, and a cam plate placed in the path of said radial arms to force them back and draw the engaged loops taut, substantially as described.

62. The combination of a ring, means for imparting an intermittent rotary motion to said ring, and a series of loop-holders hinged thereto, a cam placed in the path of said loop-holders by which they are raised from the ring and brought into an oblique position to the ring, a series of radial arms pivoted on a disk having an intermittent rotary motion corresponding with the motion of said ring, means for imparting an intermittent rotary motion to said disk, hooked links carried by said radial arms, a sliding plunger which is brought into contact with each of said radial arms successively, and connected operating mechanism for said plungers, substantially as described.

63. The combination with a ring having an intermittent rotary motion and a series of loop-holders arranged radially on said ring and hinged thereto, a stationary cam plate placed in the path of said loop-holders, a disk having an intermittent rotary motion corresponding with the motion of said ring, connected actuating mechanism by which said ring and said disk are moved simultaneously, a series of radial arms pivoted on said disk, a series of hooked links pivoted to said radial arms and engaging the knit fabric, a sliding plunger successively brought into contact with each of said radial arms, a bell-crank lever pivoted on the stationary portion of the machine and actuating said sliding plunger as described, and a projecting pin carried upon a sliding crank plate and an actuating crank, substantially as described.

64. The combination with a rotating ring having an intermittent rotary motion and carrying a series of loop-holders, loop forming mechanism, substantially as described, whereby the strand of rattan is bent into loops and placed successively upon said loop-holders, a cam-plate held in the path of said loop-holders, whereby each of said loop-holders is raised into an oblique position relatively to said ring, and a withdrawing hook engaging the loops of the knit fabric and having a motion away from said loop-holders in a line parallel with the axis of the ring, and actuating mechanism by which said hook is pushed back, substantially as described.

65. The combination of ring 30 having an intermittent rotary motion and having a projecting shoulder 112, a post 46 hinged to said ring, block 50 sliding on said post, pawl 53, pawl spring 53, tongue 51 provided with a groove 58, cam 117 held in the path of the post 46, a withdrawing hook moving in a line parallel with the axis of the ring 30, whereby the block 50 is moved down the post and the tongue 51 brought at right angles to said post, and connected actuating mechanism by which said withdrawing hook is operated, substantially as described.

66. The combination of ring 30 having an intermittent rotary motion and having a projecting shoulder 112, a post 46 hinged on said ring, sliding block 50, pawl 53, pawl spring 53^a, tongue 51 provided with a groove 58 holding the loop, stud 54, blade spring 49 provided with a hole by which it is engaged by the stud 54, a cam plate 117, and withdrawing mechanism by which the sliding blocks are moved down their posts and the tongue brought at right angles to the post, substantially as described.

67. The combination of ring 30, post 46 hinged to said ring, sliding block 50, tongue 51, pawl 53, spring 53^a, shoulder 112, blade spring 49 provided with a hole to receive the pin 55, stud 54, cam plate 117, and withdrawing mechanism engaging the loops of the knit fabric, whereby the sliding block 50 is moved down the post and the tongue 51 brought at right angles to the post, substantially as described.

68. The combination of ring 30, post 46 hinged to said ring, sliding block 50, tongue 51, pawl 53, shoulder 112, spring 49, stud 54, cam 117, hooked link 124, radial arm 123, pivoted on a disk 121, and cam 126, as and for the purpose set forth.

69. The combination of ring 30, post 46 hinged to said ring, sliding block 50, tongue 51, pawl 53, stud 54, spring 49, cam 117, hooked link 124, radial arm 123, cam 126, cam 131, cam 134, a sliding plunger by which the radial arm is pushed back, and connected actuating mechanism by which said sliding plunger is moved, substantially as described.

70. The combination of ring 30, post 46 hinged to said ring, sliding block 50, tongue 51, pawl 53, stud 54, spring 49, cam 117, hooked link 124, radial arm 123, cam 126, cam 131, cam 134, a sliding plunger by which said radial arm is pushed back, and means for actuating said plunger, substantially as described.

71. The combination of a ring having an intermittent motion and carrying a series of loop-holders, a disk whose axis is coincident with the axis of said ring, a series of radial arms pivoted on said disk, hooks carried by the free ends of said radial arms and arranged to engage the knit fabric and actuating mechanism connected with said ring and said disk, whereby said ring and said disk are moved simultaneously, substantially as described.

72. The combination with a rotating disk and the loop withdrawing mechanism, substantially as described, of a gear wheel, attached to said disk, a rack having a reciprocating motion and a rocking bell-crank lever connected with said rack, whereby the rack is alternately carried into engagement with said gear wheel and removed therefrom, by which an intermittent rotary motion in one direction is imparted to said gear wheel, an actuating cam by which said reciprocating rack is moved, an intermediate connecting mechanism and an actuating cam by which said rocking bell crank lever is moved and in-

termediate connecting mechanism, substantially as described.

73. The combination with a disk and the withdrawing mechanism, substantially as described of the disk feeding mechanism, comprising the gear wheel 136, reciprocating rack 145, oscillating bell-crank having arms 137 and 139, oscillating lever 146, links 137^a and 148, oscillating lever 8, and radial arm 12 and actuating cams 7 and 11, substantially as described.

74. The combination with a disk and the withdrawing mechanism, substantially as described, of the gear wheel 136, reciprocating rack 145, oscillating bell-crank lever having arms 137, 138 and 139, lever 141, having a locking tooth 143, and connected actuating mechanism by which said parts are operated, substantially as described.

75. The combination of a ring, a series of loop-holders, a disk carrying loop withdrawing mechanism, and an oscillating lever carrying loop-forming mechanism, all having concentric axes, actuating cams 7 and 11 and intermediate connecting mechanism by which said ring and disk and lever are simultaneously and synchronously operated by said actuating cams, substantially as described.

76. The combination in a machine for knitting rattan, of a ring carrying a series of loop-holding devices and mechanism for withdrawing the loops, substantially as described, said withdrawing mechanism and said ring having a simultaneous intermittent rotary motion in one direction, a reciprocating needle by which the strand of rattan is bent into loops and strand holding devices for retaining the strand of rattan from displacement while the loop is being formed, and connected operating mechanism by which said parts are actuated, substantially as described.

77. In a machine for knitting rattan, the combination of a ring carrying a series of loop-holding devices and mechanism, substantially as described, for withdrawing the loops consisting of a disk carrying a series of pivoted levers provided with withdrawing hooks upon their free ends, said withdrawing mechanism and said ring having a simultaneous intermittent rotary motion in one direction, a reciprocating needle by which the strand of rattan is bent into loops, a rotating crank and connected mechanism by which said needle is reciprocated, strand-holding jaws having a rocking motion in a plane at right angles to said ring, connected means for actuating said strand-holding jaws, parallel walls inclosing the strand of rattan and holding the same from lateral displacement, said strand-holding jaws being capable of a lateral movement corresponding with the angular movement of said ring and connected mechanism by which said lateral movement of the strand-holding jaws is effected, substantially as described.

78. The combination with radial arm 123 and hooked link 124, of a sliding plunger com-

prising the tube 152, inclosed rod 162 provided with a shoulder 163, and interposed spring 164, with mechanism for actuating said plunger, substantially as described.

5 79. The combination with the radial arm 123 and hooked link 124, of tube 152, inclosed rod 162 spring 164, bell-crank having arms 154, 155, pin 157, crank plate 23 and crank pin 21 and retractile spring 159, substantially as 10 described.

80. In a machine for knitting rattan, the combination with a reciprocating needle for bending the strand of rattan into loops, of a prong or jaw serving as a fulcrum around 15 which said strand is bent, said prong or jaw being fluted so as to slightly indent the surface of the rattan, substantially as described.

81. In a machine for knitting rattan, the strand conducting device comprising a strand tube having an internal diameter corresponding to the size of the strand, said tube being placed parallel with a reciprocating needle, and having a funnel shaped opening at its lower end, a tube entering said funnel shaped opening and having a diameter larger than 25 the strand, and a reciprocating needle by which said strand is drawn through said strand tube, all combined, substantially as described.
